US00D982013S

(12) **United States Design Patent** (10) **Patent No.:** **US D982,013 S**
Cai (45) **Date of Patent:** **** Mar. 28, 2023**

(54) **HUB**

(71) Applicant: **SHENZHEN DEONE INNOVATION TECHNOLOGY CO., LTD**, Shenzhen (CN)

(72) Inventor: **Xueliang Cai**, Shenzhen (CN)

(73) Assignee: **SHENZHEN DEONE INNOVATION TECHNOLOGY CO., LTD**, Shenzhen (CN)

(**) Term: **15 Years**

(21) Appl. No.: **29/847,674**

(22) Filed: **Jul. 27, 2022**

(30) **Foreign Application Priority Data**

Jul. 14, 2022 (CN) 202230447444.5

(51) **LOC (14) Cl.** **14-02**

(52) **U.S. Cl.**

USPC **D14/433; D14/434**

(58) **Field of Classification Search**

USPC D14/203.1-203.3, 348, 356-358, 363,

D14/367-369, 432-438, 480.1-480.7,

D14/484.1; D13/103, 107-108, 110, 158,

D13/168-169

CPC G06F 2213/38; G06F 2213/4004; G06F

2213/4002

See application file for complete search history.

(57) **CLAIM**

The ornamental design for a hub, as shown and described.

DESCRIPTION

FIG. 1 is a perspective view of a hub showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the hub of FIGS. 1-8 in an alternate configuration of use.

The broken lines in the drawings depict portions of the hub that form no part of the claimed design.

1 Claim, 9 Drawing Sheets
